UNITED STATES PATENT OFFICE.

DIANA E. TREVINO, OF ROMA, TEXAS.

GARMENT HANGER.

Application filed August 23, 1927. Serial No. 214,809.

This invention relates to a garment hanger, and its object is to provide a device of this character which will support a coat, or similar article of apparel and hold same suspended in such a way as to prevent its wrinkling, or losing its proper form or appearance.

It is further designed to fold in a neat and compact manner for packing in luggage receptacles, or for putting in a convenient place when not in use.

Novel forms of construction for the accomplishment of the aforesaid objects are shown in the accompanying drawings, and these together with other objects and advantages of the device will be fully disclosed in the following specification and claims.

In the drawings:

Fig. 1 shows a front view of the hanger in its open position and ready for use.

Fig. 2 shows the same folded in its closed position.

Fig. 3 shows a side view of the hanger as illustrated in Figure 2.

Fig. 4 shows a fragmentary enlargement of the roller element taken within the limits of the line 4-4 of Figure 3.

Fig. 5 shows an enlarged fragmentary view of a snap catch which may be applied at the top of the hanger joint.

Fig. 6 shows another arrangement of the wire elements employing a double form of construction.

Fig. 7 shows a front view of the parts illustrated in Figure 6.

Fig. 8 shows a top view of the parts shown in Figure 7.

Referring first to Figure 1 of the drawings, the device comprises right and left shoulder members as seen at 10 and 11, these are preferably made of wood, but may be of any suitable material. At their inner ends they are connected by the hinge 12 which is affixed by screws, or like means. A supporting frame 13 is formed of wire of a proper gauge and is provided with a loop 14, a bridge piece 15 and spreading guide members 16 and 17 which are formed by bending the side wires back from their extremities to positions parallel to their outer parts, thus providing in each member an elongated space as seen at 18 and 19. The said guide members are secured together at their ends by a connecting member 20, which may be welded, or otherwise secured thereto.

The supporting frame 13 is slidably se-

cured to the shoulder members by the pivot screws 21 and 21' which are provided with rollers as will be hereinafter described, and with washers as seen at 22 and 23 which rest against the guide members. The form of the aforementioned rollers is illustrated in Figure 4 at 24. It provides ease of movement when it is desired to close, or to open the hanger.

A snap catch as shown in the enlarged fragmentary view in Figure 5, may be applied at the top of the shoulder joint if desired. As illustrated, it comprises a spring leaf 25 which is secured to a shoulder member by the pin 26. A hole as indicated at 27 engages a stud 28 which is driven into the adjacent shoulder member. The joint may be released by lifting the leaf by the tip 29.

Another form of the invention is shown in Figures 6, 7 and 8, in which the supporting frame is of double construction and engages both sides of the shoulder members. This construction is as follows. The outer wires of the guide members which will here be numbered 30 and 31, extend upward to a point under the ring 32 where they are bent inward and around the shank 33. The corresponding wires of the opposite guide members as seen at 34 and 35, extend upward in a similar manner and are bent around the shank adjacent to those first mentioned. The said shank 33 is integral with the ring 32 and has a washer 36 above its upset end. It will be seen that the ring thus attached is free to swivel within the joint. A hook may be substituted for this ring if preferred.

While I have shown the invention in its preferred forms, I do not wish to be held rigidly to the exact details of construction as illustrated, but claim the right to such minor modifications as may come within the scope of the appended claims.

Having thus described my invention, what I claim as new and desire to secure by Letters Patent, is as follows:

1. In a garment hanger, a pair of shoulder members hingedly connected at their inner ends and adapted to bear against each other above the point of the said hinged connection, a supporting frame of inverted Y formation having guide elements provided with elongated open spaces closed at their lower extremities, and flanged pivot members passing through the said open spaces and bearing freely against the sides of the said guide elements, means to

limit the spread of the said guide elements at their lower ends, and means to support the frame elements above the upper portions of the said guide members, and 5 means to suspend the whole from any suitable object.

2. In a garment hanger, shoulder members of suitable form, hinged together at their inner extremities and adapted to bear 10 against each other above the point of hinged connection, a supporting frame of suitable wire material formed with a loop element at the top and connected by a bridge member below the said loop and extending below 15 the said bridge member in inverted Y formation having the lower elements thereof looped around at their ends and extending backward in positions parallel to their outer parts thus forming elongated open spaces 20 which converge at their upper extremities, and a connecting piece between the extremities of the said lower elements, and the said supporting frame secured to the aforesaid shoulder members by means of flanged pivots 25 passing through the said open spaces and having rollers around the shanks thereof which bear against the sides of the aforesaid lower elements.
3. In a garment hanger, suitably formed 30 shoulder members hinged together at their inner ends and adapted to bear against each other above this point of connection, a supporting frame of inverted Y formation slidably secured to the said shoulder members

by means of flanged pivots passing through 35 open spaces in the legs thereof, and a snap catch in the form of a leaf spring secured to one of the said shoulder members near to the point of its contact with the opposite member, and the said leaf spring provided 40 with a hole adapted to engage a stud in the adjacent shoulder member, substantially as shown and described.

4. In a garment hanger, suitably formed shoulder members hingedly connected at 45 their inner extremities and adapted to bear against each other above the point of connection, a supporting frame slidably secured to the said shoulder member and the said frame of the following construction, 50 front and back elements each in the shape of an inverted Y and formed of suitable wire material, the downward depending legs of the said front and back elements each having an elongated opening between the side 55 members thereof and each leg being secured to its adjacent shoulder member by means of a flanged pivot imbedded in the said member and bearing freely against the said leg, and the said front and back elements 60 joined together at the top by means of looped portions bent around the shank of a swivel supporting element, substantially as shown and described.

In testimony whereof I have affixed my 65 signature.

DIANA R. TREVINO.
